UNITED STATES PATENT OFFICE.

CHARLES F. BENNETT, OF BRIDGEPORT, CONNECTICUT.

HAT-BAKING OVEN.

933,413.

Specification of Letters Patent.

Patented Sept. 7, 1909.

Application filed March 17, 1909. Serial No. 484,020.

To all whom it may concern:

Be it known that I, CHARLES F. BENNETT, a citizen of the United States, residing at Bridgeport, in the county of Fairfield and 5 State of Connecticut, have invented certain new and useful Improvements in Hat-Baking Ovens; and I do hereby declare the following to be a full, clear, and exact description of the invention, such as will enable 10 others skilled in the art to which it appertains to make and use the same.

My invention relates to certain improvements in hat baking ovens, and has for its object to provide an oven of this description 15 which shall be surrounded by steam inclosing walls and in which a steam inclosing partition shall separate the oven into two compartments each compartment being accessible from opposite sides of the oven, the 20 partition compartment being so arranged and supported that there can be no danger of the straining of any of the steam inclosing elements by the inequalities of expansion and contraction.

25 With these ends in view my invention consists in the details of construction and arrangement of parts hereinafter fully described and then particularly pointed out in the claims which conclude this description.

In the accompanying drawing Figure 1 is a perspective view of my improvement—Fig. 2 a section at the line x, x , of Fig. 3, and Fig. 3 a section at the line y, y , of Fig. 2.

35 Similar numbers of reference denote like parts in the several figures of the drawing.

Heretofore, in hat baking ovens, steam inclosing spaces have been provided for furnishing the proper degree of heat, and also 40 the oven has been divided into compartments by steam inclosing walls, but since the steam inclosing frame which surrounds the oven is exposed to the external atmosphere, whereas the steam inclosing partition is internal of 45 the oven, the inequalities in expansion and contraction have strained the steam inclosing elements to the extent that they would leak steam thereby either ruining the hats or causing them to be depreciated to the extent 50 that they are marketed as "seconds".

My improvement obviates these defects and will be readily understood from the following description:—

The surrounding side walls of my improved oven are composed of two concentric metal walls 1, 2, separated by a space 3 and

retained in position by means of suitable rivets or bolts 4 extending through said walls. The steam inclosing partition is composed of two parallel walls 5, 6, united at 60 their peripheries by welding and held in position as against collapsing by means of suitable rivets 7 extending through said walls. Instead of expanding these walls 5, 6, directly into the inner surrounding wall 65 2, or else securing the ends of these walls directly and immediately to said side wall, I employ angle brackets 8 whose extremities are secured respectively to the inclosing walls 1, 2, and the walls 5, 6, of the inner 70 partition, so that the latter will be in effect suspended within the drum without any direct connection with the surrounding walls. The oven is provided with shelves 9 on which the hats are placed for the purposes of baking, and any suitable doors 10 are arranged in the ends a, b , of the oven whereby access 75 is given to the latter.

11 is the steam inlet pipe which communicates through the side extension 12 with the 80 surrounding steam inclosing space that is formed by the walls 1, 2.

13 is a pipe extending from said steam inlet and communicating with the steam inclosing space formed by the partition walls 85 5, 6.

14, 15, are extension pipes which lead from the steam inclosing partition and the steam inclosing drum respectively and communicate with the exhaust pipe 16. It will therefore be clearly understood that the space 90 inclosed by the surrounding walls and by the internal partition are in the same steam circuit.

When the oven is heated and subsequently 95 cooled the internal partition can never exert any strain against the surrounding walls owing to the inequalities of expansion and contraction, but such inequalities will be taken up by the brackets 8 and will have no appreciable effect upon the walls 1, 2.

By the use of my improvement there is no likelihood of steam leakage such as would affect the hats in the oven, and no especial care need be taken in the heating and cooling 105 of the oven.

Having thus described my improvement what I claim as new and desire to secure by Letters Patent is:—

1. A hat baking oven, comprising surrounding steam inclosing walls, end caps secured to said walls, a steam inclosing parti-

tion within said oven and having no direct contact with said walls, means for providing said partition and walls with inlet and outlet for steam, shelves within the oven, and doors within said end caps whereby access is had to the oven.

2. A hot baking oven, comprising a surrounding steam inclosing drum, a steam inclosing partition within said oven and having no contact with said drum, brackets secured to said partition whereby the former is held in position, caps secured to opposite

ends of said drum and provided with doors, shelves within said oven on opposite sides of said partition, and steam inlet and exhaust 15 pipes communicating with said drum and partition.

In testimony whereof I affix my signature in presence of two witnesses.

CHARLES F. BENNETT.
